CLAIM

The ornamental design for a steering wheel as shown and described.

DESCRIPTION

FIG. 1 is a front view of a steering wheel of our present design;

FIG. 2 is a rear view thereof;

FIG. 3 is a right side view thereof;

FIG. 4 is a left side view thereof;

FIG. 5 is a top view thereof;

FIG. 6 is a bottom view thereof; and,

FIG. 7 is a front right perspective view thereof.

Portions of the steering wheel surrounded by broken lines form no part of the claimed design.
